(57) CLAIM

The ornamental design for a kick and balance trainer, as shown and described.

DESCRIPTION

FIG. 1 is a perspective rear view of the kick and balance trainer of the present invention;

FIG. 2 is a perspective front view of the kick and balance trainer shown in FIG. 1;

FIG. 3 is a top view of the kick and balance trainer shown in FIG. 1;

FIG. 4 is a left side view of the kick and balance trainer shown in FIG. 1;

FIG. 5 is a rear view of the kick and balance trainer shown in FIG. 1; and,

FIG. 6 is a front view of the kick and balance trainer shown in FIG. 1.

The broken line showing of the wheels is included for the purpose of illustrating environmental structure and forms no part of the claimed design.
